(57) **CLAIM**

The ornamental design for a combination pipe coupling and anchoring clamp as shown and described.

DESCRIPTION

FIG. 1 is a side front perspective view of a combination pipe coupling and anchoring clamp showing the new design;

FIG. 2 is a front elevational view thereof with the rear elevational view being a mirror image;

FIG. 3 is a top plan view thereof with the bottom plan view being a mirror image;

FIG. 4 is a first side view thereof with the second side view being a mirror image;

FIG. 5 is a front side perspective view of the combination pipe coupling and anchoring clamp of FIG. 1 shown in use fastened to and around unclaimed environmental structures; FIG. 6 is a front side perspective view of the combination pipe coupling and anchoring clamp of FIG. 1 shown in use fastened to and around unclaimed environmental structures; and,

FIG. 7 is a front side perspective exploded view of the combination pipe coupling and anchoring clamp of FIG. 1. The broken lines depict portions of the combination pipe coupling and anchoring system that form no part of the claim. Additional broken lines in FIGS. 5 and 6 depict environmental subject matter that forms no part of the claimed design.
